UNITED STATES PATENT OFFICE

WILLIAM T. JOHNSON, OF NEW BRIGHTON, PENNSYLVANIA, ASSIGNOR TO MAYER CHINA COMPANY, OF BEAVER FALLS, PENNSYLVANIA, A CORPORATION OF PENNSYLVANIA

DESIGN FOR A PLATE OR SIMILAR ARTICLE

Application filed July 12, 1932. Serial No. 44,313. Term of patent 14 years.

To all whom it may concern:

Be it known that I, WILLIAM T. JOHNSON, a subject of Great Britain, residing at New Brighton, in the county of Beaver and State of Pennsylvania, have invented a new, original, and ornamental Design for a Plate or Similar Article, of which the following is a specification, reference being had to the accompanying drawing, forming part thereof.

In the drawing:

The figure is a face view of the plate, partly broken away, showing my new design, the border decoration illustrated in detail extending entirely around the circumference of the plate.

I claim:

The ornamental design for a plate or similar article, as shown and described.

WILLIAM T. JOHNSON.
